UNITED STATES PATENT OFFICE.

WILLIAM J. FLOWERS, OF RONDO, MISSOURI.

CULTIVATOR.

SPECIFICATION forming part of Letters Patent No. 284,403, dated September 4, 1883.

Application filed April 27, 1883. (No model.)

To all whom it may concern:

Be it known that I, WILLIAM J. FLOWERS, of Rondo, in the county of Polk and State of Missouri, have invented a new and Improved 5 Two-Row Corn-Cultivator, of which the following is a full, clear, and exact description.

This invention pertains to an improvement in cultivators; and it consists of the combination and arrangement of parts, substantially 10 as hereinafter fully set forth and claimed.

Reference is to be had to the accompanying drawings, forming a part of this specification, in which similar letters of reference indicate corresponding parts in both figures.

15 Figure 1 is a plan view of my two-row cultivating-machine. Fig. 2 is a rear elevation of the same.

A is the axle, which is arched twice and in a similar manner to two-horse cultivators. 20 On this axle are hung four double plows, B, or four sets of double shovels similar to those used in ordinary cultivators, and these are connected in pairs by bent connecting-rods C, so that one handle, G, connected to each rod, 25 shall serve to raise and lower both plows of the pair, thereby rendering it unnecessary to have more than two handles.

To the arches of the axle A are connected shafts D D, which are arranged for using three 30 horses. The shafts are provided next to the

axle with double-trees E, which serve to equalize the draft, and upon the outer ends of the shafts are neck-yokes F, which also act as equalizers.

With a cultivator of this construction three 35 horses can be used and two rows of corn operated on at once, thus doing the work of two ordinary corn-cultivators with less labor and in less time.

I am aware that it is not new to adapt a cul- 40 tivator for use with a team of three horses, nor for the simultaneous cultivation of two rows of corn.

Having thus described my invention, I claim as new and desire to secure by Letters Patent— 45

In a cultivator, the combination, with the axle A, having a depressed middle portion and elevated side portions, and the draft-bars D, attached to said elevated portions of the axle, of the draft-equalizer consisting of the 50 whiffletrees E, arranged upon the draft-bars and connected together at their inner ends, the chain effecting this connection being connected by a second chain to the depressed middle portion of the axle, and of additional whiffletrees, essentially as shown and described. 55

WILLIAM J. FLOWERS.
